United States Patent Office.

CHENEY KILBURN, OF PHILADELPHIA, PENNSYLVANIA, ASSIGNOR TO
KILBURN & GATES, OF SAME PLACE.

Design No. 4,357, dated September 20, 1870.

DESIGN FOR BOXES FOR TOPS OF BUREAUS.

The Schedule referred to in these Letters Patent and making part of the same

I, CHENEY KILBURN, of Philadelphia, county of Philadelphia, State of Pennsylvania, have invented a Design for Boxes for the Tops of Bureaus, of which the following is a specification.

On reference to the accompanying drawing—

Figure 1 is a perspective view of a box made in accordance with my design;

Figure 2, a plan view of the same;

Figure 3, a sectional view, representing the design of the molding for the edge of the box; and

Figure 4 is a perspective view, representing a molding of a different design.

The peculiar shape of the box, which is the main feature of my design, will be best observed in the plan view, fig. 2, where it will be seen that the box has a curved front, *a*, and ends *b b*, parallel with each other, and at right angles to the back *c*, the ends joining the curved front at an angle, so as to form projecting corners, *x x*.

The design of the molding or finish for the edge of the box is of the character shown in fig. 3, its main

peculiarity being the square projecting base *h*, beneath the outwardly rounding portion *i* of the molding.

The portion *i* of the molding may be perfectly plain, or may be carved in imitation of a spiral coil or rope, as shown in fig. 4.

I claim—

1. The design for the shape of a box for the tops of bureaus, substantially as described, and as represented in and by the accompanying drawing.

2. The said box, ornamented as shown and described in fig. 4.

In testimony whereof I have signed my name to this specification in the presence of two subscribing witnesses.

CHENEY KILBURN.
